UNITED STATES PATENT OFFICE

2,502,262

FLUSHING TANK

Sidney H. Labiche, New Orleans, La., assignor of
one-half to Acadian Business Corporation, New
Orleans, La., a corporation of Delaware

Application October 2, 1945, Serial No. 619,841

1 Claim. (Cl. 4—26)

1

My present invention relates to toilets and has for an object to provide a water tight flushing tank.

Another object of my invention is to provide a flushing tank having a free water inlet.

Another object of my invention is to provide in a flushing tank a spring actuated valve for closing the water outlet thereof.

A still further object of this invention is to provide a flushing tank having only one movable member.

A still further object of the invention is to provide a water and air tight flushing tank.

Other features and advantages will become more readily apparent from the following description and the accompanying illustrative drawings in which:

Figure 1 is a sectional view of my tank taken on line 1—1 of Figure 3.

Figure 2 is a similar view taken on line 2—2 of Figure 3, certain parts being removed.

Figure 3 is a sectional view taken on line 3—3 of Figure 1, and

Figure 4 is a section on line 4—4 of Figure 1.

My device 10 consists of a tank 11 within which is provided a vertical compartment 12 having side walls 13 and 14, preferably formed integral with the walls 15 and 16 of the tank. Said compartment is divided by an intermediate horizontal wall 17 integral with walls 13 and 14, whereby the said compartment is divided into upper or pressure and lower or valve chambers 18 and 19. An inner wall 20 closes said chambers by means of thumb screws 21 and 22, a gasket 23 sealing the connection between said wall 20 and the edges 24 and 25 of walls 13 and 14, to which it is sealed by said screws.

A top wall 26 is provided for the tank which seats upon a gasket 27, seated upon the upper edge 28 of the tank, the wall 26, being secured by screws 29. The walls 13, 14 and 20 have the upper edges 30, 31 and 32 sealed by a gasket 33, upon which the inner surface 34 of top 26 seats. The said top is provided with an integral depending boss 35 of a dimension to fit snugly into the upper end 36 of chamber 18, and forms a cap therefor.

Aligning bores 36' and 37, are provided in the members 17 and 35 to receive the plunger rod 38, which operates slidably therein and is normally held in down position by a spring 39, coiled there-around and held between the cap 35 and pin 40 on said rod. The bore 37 is enlarged and inclined at its upper portion 41 to receive packing 42, held compressed by a screwed-in cap 43.

2

The bore 36' also extends into similar packing gland 44, provided in wall 26.

The lower end 53 of chamber 19 is of inverted conical form and is provided with three ports 45, 46 and 47, through walls 20, 13 and 14, respectively, which lead into the water chamber 48 of the tank. Mounted directly above said ports is a tubular collar 49, within which is slideable a valve 50 having a cylindrical head 51, snugly fitting the said collar 49, and a tapering lower end 52 conforming to the contour of the said end 53, the upper edge 54 of which forms a seat for the collar 49. The valve member 50 is fixed to the lower end 55 of rod 38, whereby upon drawing up of the rod against the tension of spring 39 by means of the button 56 on the outer end 57 of the rod, the said ports 45, 46 and 47 will be opened to permit water in the chamber 48 to flow out through the outlet port 58 of the tank and into the brass pipe 59 screwed into the bottom wall 16 of the tank and leading to a toilet seat. An inlet pipe 60 threaded into bore 61 of said tank permits water to flow into and fill the chamber 48.

In order to permit the chamber 48 to become substantially full of water, a small air passage 62 may be provided in the upper end of wall 13 for air to escape into compartment 18 of member 12. As the tank fills to near its top the pressure of air in said compartment will become greater than the pressure of water in inlet pipe 60 so that a certain amount of air will be trapped in the extreme upper end 63 of the tank which will hold the extreme upper water line at a point 64 below the vent 62, thus preventing water from passing therethrough. Any other suitable valve means may be substituted for preventing air trapped in the tank from overcoming the water pressure and preventing filling of the tank.

From the foregoing it becomes evident that I have invented a meritorious flushing tank which can not become out of order under ordinary circumstances.

Having now described my invention that which I claim as new and desire to procure by Letters Patent is:

A liquid storage and flushing device comprising a liquid retaining tank, a closure having an opening with a sealing gland, said closure being normally in sealing engagement with said tank, a liquid inlet in said tank, means forming a compartment in said tank, a substantially horizontal partition in said compartment separating it into a lower valve chamber and an upper pressure

chamber, said partition having an aperture surrounded by a sealing gland, an outlet for said tank communicating with said valve chamber, a hollow head disposed slidably in said valve chamber and resilient means pressing said valve head normally seated on said valve seat, a slideable valve stem extending from said valve head and extending through said chambers and terminating exteriorly of said tank for manually operating said valve, said stem being passed through said sealing glands, and an air passage in said pressure chamber to receive air under pressure from said tank as liquid enters said tank through said inlet, and means forming a passageway and arranged to be controlled by 15 said valve head for conducting liquid from said tank to and into said outlet.

SIDNEY H. LABICHE.
